Primary Examiner — Mary Ann Calabrese*Assistant Examiner* — Sloan Rozin(74) *Attorney, Agent, or Firm* — Lorenz & Kopf, LLP(57) **CLAIM**

The ornamental design for a display screen with graphical user interface, as shown and described.

DESCRIPTION

FIG. 1 is a front view of a first embodiment of the display screen with graphical user interface; and, FIG. 2 is a front view of a second embodiment of the display screen with graphical user interface. The broken line showing of the display screen is for the purpose of illustrating environment and forms no part of the claimed design. The broken line showing of elements on the display screen illustrate portions of the article and form no part of the claimed design.

1 Claim, 2 Drawing Sheets(56)
